FASTENING MEANS FOR TROUSERS AND
OTHER GARMENTSMarcus Manly Isaacs, Sydney, New South
Wales, AustraliaApplication January 10, 1946, Serial No. 640,210
In Australia January 11, 1945

4 Claims. (Cl. 2—237)

1

In connection with trousers, skirts and other garments it is known to provide means for supporting and/or fastening or securing same at the waistband. Frequently such means comprise a flap or extension band, and a hook-and-eye device the parts of which are permanently secured to said flap and to some other part of the waistband, respectively, for instance to a second flap.

Both the hook and the eye of the device are frequently of a width corresponding to that of the flap or other part of the band, or secured to them by tapering sections. Nevertheless, experience has proved that the tightening strain is taken only by a narrow portion, or portions, of the flap (flaps) and waistband so that these become wrinkled and distorted in use, the result being that the trousers or other garment become uncomfortable in wear and the waistband itself is of unsightly appearance.

It is one object of the present invention to provide an improved hook-and-eye device for supporting and/or fastening means of the kind referred to, so designed as to assure even distribution of the strain all over the width of the flap (flaps) and other parts of the waistband.

A further object of the invention is to provide an improved design of waistband suitable for the use of the hook-and-eye device according to this invention.

A still further object of the invention is to provide a hook-and-eye device the members of which, though firmly retained in the garment during use, are so attached thereto that they may be easily removed therefrom—for instance whilst the garment is being cleaned or pressed—and can be re-attached by a simple operation not requiring any skill.

With these objects in view the fastening means according to the invention comprises separate hook and eye members each of which has a base element, whereas the garment is provided with pouches for the accommodation of the base elements of the hook member and of the eye member, respectively, the transverse width and the contour of each base element corresponding to the width and contour of the pouch for its accommodation and the arrangement of the pouches in the garment and the construction of the members being such that, when the garment is closed in wear, the base elements transfer the closing strain uniformly over the entire widths of the pouches and thus keep the section of the garment containing the pouches in taut condition.

2

On a garment equipped for fastening means according to the invention the pouches are provided in pairs in a section or sections to be closed, for instance in a proper section or sections of its waistband. These pouches may be permanently open to permit detachment of the members of the fastening means whenever required, and the said members may accordingly be formed as clips which may be attached to the garment without sewing.

In order to more particularly describe the invention, reference is made to the accompanying drawing which, by way of example, illustrates some specific forms of the improved fastening means and its use on the waistband of self-supporting trousers, and wherein:

Fig. 1 is a fragmental perspective view showing a section of a waistband of trousers;

Figs. 2 and 3 are perspective views of one form of hook member and eye member, respectively, of the fastening means;

Fig. 4 is a diagrammatic sectional view illustrating members of the fastening device similar to those shown in Figs. 2 and 3, as applied to the waistband section shown in Fig. 1;

Figs. 5 and 6 are perspective views showing a modified form of hook member and eye member, respectively, of the fastening means;

Figs. 7 and 8 are perspective views showing another modified form of the fastening means according to the invention, Fig. 8 illustrating the said fastening means applied to the waistband of a garment.

The waistband section illustrated in Fig. 1 includes two spaced flaps A and A'. Each of these flaps is formed with a pouch B and B', respectively, of a suitable depth, and of a width w which substantially equals that of the flap in which it is formed. The pouches B and B' are each adapted to accommodate one of the separate members—hook member C and eye member D, respectively—of the fastening means according to the invention.

The hook member C as shown in Fig. 2 comprises a thin plate element 10 the transverse width of which equals the width w of the pouch B wherein it is accommodated for use. The contour of the end 11 of element C corresponds accurately to that of the bottom of the pouch B. At its opposite end the element C is doubled back to form a tongue 12 the end or tip 12 of which is returned again to form the hook proper of the device.

The eye member D of the device which is shown in Fig. 3 also comprises a thin plate element 13 the transverse width w of which equals

that of the pouch or pocket **B'** in which it is accommodated for use. The contour of the end **d** of the element **D** corresponds accurately to that of the bottom of the pouch **B'**. At its opposite end the element **D** is formed with an extension or tongue **14** which is returned and is formed to constitute the eye portion proper of the device. In the form shown the extension **14** is provided with a number of spaced slots **15** each of which constitutes an eye in which the hook **12** of the fastening device may selectively be placed in use, for instance in the manner shown in Fig. 4.

The plate elements **C** and **D** may be perfectly flat as shown in Figs. 2 and 3. However, if so desired, they may be slightly curved in the manner depicted in Fig. 4 to correspond to the contour of the closed garment while in use.

When the fastening device is used, the strain to be taken is transmitted from the waistband to the operative parts of the device via the above described two plate elements **C** and **D**, each of which bears with its end **c** and **d** against the bottom of the pouch **B** and **B'**, respectively, in which it is located, engaging the said bottom over its entire width **w**. Thus the elements **C** and **D** tension the flaps **A** and **A'** of the waistband across their entire widths, thereby preventing the formation of wrinkles, folds and other distortions of the waistband during wear of the garment of which it forms part.

Preferably the apertures **E** and **E'**, respectively, through which the two plate elements **C** and **D** of the hook-and-eye device are inserted into the respective pouches **B** and **B'**, remain open, and thus the members **C** and **D** are detachable from the pouches into which they are placed for use, so that they may be easily removed therefrom, for instance while the trousers or other garment is being cleaned or pressed. Accordingly 40 the tongues **11** and **14**, respectively, of the two members **C** and **D** are preferably made to spring against their respective base plates and thus to act as clips which prevent undesired disengagement of the members **C** and **D** from the pouches **B** 45 and **B'**.

Alternatively, the apertures **E** and **E'** may be closed after insertion of the members **C** and **D**, for instance by sewing, if it is desired to secure the fastening members permanently to the 50 trousers or other garment.

With particular advantage the fastening device according to the invention may be applied to waistbands with flaps made by a press-folding process over a mould or die the shape of which corresponds to that of the abovedescribed plate elements. This process assures perfect accuracy of the shape and size of the flaps as well as of the pouches formed therein. However, the fastening device according to the invention is also applicable to flaps and other parts of waistbands made by some other method.

In the modified form of the members of the fastening device shown in Figs. 5 and 6, both the hook element **C'** and the eye element **D'** consist entirely of suitably profiled frame structures 20 and **23** respectively, made for instance of pressed steel. Here again the contour of the ends **c'** and **d'** of the elements **C'** and **D'**, respectively, are shaped to correspond to the shape 70 of the bottom of the pouches **B** and **B'** of the flaps **A** and **A'**.

In Fig. 5 the tongue of the hook member **C'** is designated by **21** and the returned tip which forms the hook proper of the member, by **22**.

In Fig. 6 the tongue of the eye member **D'** is designated by **24**. As may be seen it is, in this case, formed with two spaced transverse bars **25** to which the hook **22** may be attached selectively.

When inserted in the pouches **B** and **B'**, the members **C'** and **D'** are slightly elastically compressed and thereby keep the flaps or other part of the waistband in taut condition. From 10 this it will be understood that the use of such resiliently compressible members is of particular advantage where perfect accuracy of the widths of the pouches and of their contours is not assured.

15 Figs. 7 and 8 shows a further modification of the fastening means according to the invention. In this form the eye member **D²** is similar to the member **D'** shown in Fig. 6, whereas the hook member **C²** differs from the aforescribed hook members by the provision, between the tongue 20 **31** and the hook proper **32**, of an expansion spring **36**. As may be seen, the spring **36** is a flat coil spring of the type known for bracelets, arm-bands and other articles.

25 In the particular arrangement shown in Fig. 8 only a small section of the flat spring **36** is visible in wear, the ends of the spring being covered by extensions **A²** and **A³** of a waistband **H**, in pouches **B²** and **B³** of which the members **C²** and **D²** of the device are accommodated. It will be seen that the arrangement shown in Fig. 8 is of slight appearance and is therefore particularly suitable for use in outer wear of any description, including self-supporting trousers.

30 35 The members of the fastening device according to the invention may be made of metal or, alternatively, of any other solid material—for instance plastic material—or combination of materials.

I desire it to be understood that I do not wish protection by Letters Patent to be confined to the hereinbefore-described details of the fastening device and waistband, since modifications of either are feasible within the scope and ambit of the invention.

Thus the configuration of the members, their parts, and of the flaps or other parts of the waistband, may be varied to meet different requirements, and changes of fashion.

The fastening device according to this invention may be used on any kind of garment and in any appropriate arrangement. It may be used in any of the manners described or, alternatively, in combination with any other elastic and/or adjustable tensioning means such as rubber or other elastic bands and/or strap and buckle devices.

I claim:

- Fastening means for a garment having opposed flaps, including two pouches each having a closed bottom and an open mouth, said pouches being provided for securing to the opposed flaps of said garment with the open mouths oppositely and outwardly directed, a hook member, and an eye member, each of said members having a base formed with a tongue arranged in spaced juxtaposition to the base, said tongues being positioned outside said pouches and extending with their free ends toward each other when said bases are loosely inserted into said pouches, the hook member having its tongue provided with a hook adapted to engage an eye provided on the tongue of said eye member, said base members having a transverse width and end contour conforming to the width and bottom contour of the pouches, said base members being

urged into engagement with the bottom of their respective pouches when said hook and eye are operatively connected with each other.

2. Fastening means for a garment having opposed flaps, including two pouches each having a closed bottom and an open mouth, said pouches being provided for securement to the opposed flaps of the garment with the open mouths oppositely and outwardly directed, a hook member, and an eye member, each of said members having a base formed at one end thereof with a resilient tongue bent back upon said base so as to be spaced therefrom and substantially parallel thereto, said tongues being positioned outside said pouches and extending with their free ends toward each other when said bases are loosely inserted into said pouches, the hook member having its tongue provided with a hook adapted to engage an eye provided on the tongue of said eye member, said base members having a transverse width and end contour conforming to the width and bottom contour of the pouches, said base members being urged into engagement with the bottom of their respective pouches when said hook and eye are operatively connected with each other.

3. Fastening means for a garment having opposed flaps, including two pouches each having a closed bottom and an open mouth, said pouches being provided for securement to the opposed flaps of said garment with the open mouths oppositely and outwardly directed, a hook member, and an eye member, each of said members having a base formed with a tongue arranged in spaced juxtaposition to the base, said tongues being positioned outside said pouches and extending with their free ends toward each other when said bases are loosely inserted into said pouches, and a resiliently expansible element incorporated in one of said tongues and forming a part of the same, the hook member having its tongue provided with a hook adapted to engage an eye provided on the tongue of said eye member, said base members

having a transverse width and end contour conforming to the width and bottom contour of the pouches, said base members being urged into engagement with the bottom of their respective pouches when said hook and eye are operatively connected with each other.

4. Fastening means for a garment having opposed flaps, including two pouches each having a closed bottom and an open mouth, said pouches being provided for securement to the opposed flaps of said garment with the open mouths oppositely and outwardly directed, a hook member, and an eye member, each of said members having a base formed with a tongue arranged in spaced juxtaposition to the base, said tongues being positioned outside said pouches and extending with their free ends toward each other when said bases are loosely inserted into said pouches, and a coil spring incorporated in one of said tongues to render the same resiliently expansible, the hook member having its tongue provided with a hook adapted to engage an eye provided on the tongue of said eye member, said base members having a transverse width and end contour conforming to the width and bottom contour of the pouches, said base members being urged into engagement with the bottom of their respective pouches when said hook and eye are operatively connected with each other.
